WALTER S. COX, OF PHILADELPHIA, PENNSYLVANIA, TRADING AS GEORGE S. COX
AND BROTHER.

WARP-BEAM.

946,534.

Specification of Letters Patent. Patented Jan. 18, 1910.

Application filed April 30, 1908. Serial No. 430,198.

To all whom it may concern:

Be it known that I, GEORGE S. Cox, a citizen of the United States, residing at Fitzwatertown, county of Montgomery, and State of Pennsylvania, have invented a new and useful Improvement in Warp-Beams, of which the following is a full, clear, and exact description, reference being had to the accompanying drawings, which form a part of this specification.

10 My invention has for its object to produce a warp beam made entirely of metal, or substantially so, to take the place of the solid wooden beam heretofore most generally used.

15 In the drawings: Figure 1 is a front elevation of the beam, partly broken away; Fig. 2 is an end view of the same, and Fig. 3 is a section on the line 3—3 of Fig. 1.

20 The beam *a* consists of a hollow metal cylinder carrying the adjustable beam heads *b*, the adjustable brake pulleys *c* and the end heads *d* carrying the trunnions *e*. The wall of the beam is provided with a series of pairs of holes *f*, each pair of holes being 25 adapted to receive a cord *g*, one end of which is passed into the interior of the beam through one hole of a pair and thence to the exterior of the beam through the other hole, the cord serving as a means of fastening together a number of adjacent warp ends. Each beam head *b* is provided with 30

the annular flange *h* adapted to fit neatly on the cylinder, the fit being just sufficiently loose to enable the beam head to be moved 35 along the beam so as to adjust it to any desired position. To hold the beam head securely in its adjusted position and at the same time prevent any variations with respect to tightness of fit at different points 40 around the periphery of the beam, I insert set screws *i* into the flange *h* and arrange the screw holes, preferably four in number, at substantially equal distances around the circumference of the flange, so that each hole 45 is diametrically opposite another hole. By this means, the beam head may be firmly held at any point to which it is adjusted and at the same time the pressure of the beam head against the beam is equalized by reason of 50 the regular distribution of the set screws around the periphery of the beam.

Each brake pulley *c* is provided with an annular flange *k* and set screws *l* extending through the flange and engaging the beam.

The screw holes for screws *l* are also arranged at substantially equal distances around the flange, and the purpose of this construction is the same as that described with reference to the flange of the beam head *b* and the set screws *i*.

55 Each trunnion *e* has secured thereto the heads *d*, whose external diameter is substantially the same as the inner diameter of the beam, so that when the heads are pushed or driven into the open ends of the beam cylinder, they will fit substantially tightly therein. The heads *d* are spaced apart on the trunnion *e*, one head being fixed on the inner end thereof and the other being fixed at some distance from the inner end. The 60 trunnion *d* is moved inwardly until the outer head is substantially flush with the end of the beam cylinder. After the trunnion is thus placed in position, it may be permanently secured to the beam by means of 65 rivets *m* engaging the cylinder and the trunnion heads.

Having now fully described my invention, what I claim and desire to protect by Letters Patent is:—

70 1. A warp beam comprising a cylinder provided with a series of pairs of holes of which the holes of a pair communicate one with another in the interior of the cylinder, thereby permitting a cord to be passed 75 through both holes of a pair and tied on the outside to afford a means of fastening together adjacent warp ends.

2. A warp beam comprising a hollow cylinder provided with a series of holes extending entirely through the walls thereof, said holes being arranged in pairs of which the holes of a pair are arranged substantially nearer to each other than to the nearest hole of an adjacent pair.

95 3. A warp beam comprising a cylinder, trunnions, means by which the trunnions are secured to the ends of the cylinder, brake pulleys and beam heads, movable along the cylinder, each of which is provided with a flange having a series of pairs of screw orifices in which the screw orifices of a pair are arranged diametrically opposite to each other and in which the orifices are arranged at substantially equal distances around the circumference of the flanges, and set screws 100 in said orifices adapted to be tightened against the cylinder.

4. A warp beam comprising a hollow cylinder, trunnions, means by which the trunnions are secured to the ends of the cylinder, brake pulleys and beam heads, 5 movable along the cylinder, each of which is provided with a flange having screw orifices arranged at substantially equal distances around the circumference of the flange, and set screws in said orifices adapted

to be tightened against the smooth periphery 10 of the cylinder.

In testimony of which invention, I have hereunto set my hand, at Philadelphia, on this 28th day of April, 1908.

GEORGE S. COX.
